CLAIM

The ornamental design for a skewer with pushing component, as shown and described.

DESCRIPTION

FIG. 1 is a top isometric view of the skewer with pushing component embodying the new design.

FIG. 2 is a top isometric view of the skewer with pushing component in an alternate position.

FIG. 3 is a top view of the skewer with pushing component of FIG. 1.

FIG. 4 is a bottom view thereof.

FIG. 5 is a side view thereof with the opposing side view being a mirror image thereof

FIG. 6 is a rear view thereof; and,

FIG. 7 is a front view thereof.
